UNITED STATES PATENT OFFICE.

ERNEST WILLOUGHBY PETTER, OF YEOVIL, ENGLAND.

INTERNAL-COMBUSTION ENGINE OF THE TWO-CYCLE TYPE.

1,296,214.

Specification of Letters Patent.

Patented Mar. 4, 1919.

Application filed May 3, 1916. Serial No. 95,033.

To all whom it may concern:

Be it known that I, ERNEST WILLOUGHBY PETTER, residing in Yeovil, Somerset, England, a subject of the King of Great Britain and Ireland, have invented certain new and useful Improvements in or Relating to Internal-Combustion Engines of the Two-Cycle Type, of which the following is a specification.

10 This invention relates to two cycle internal combustion engines of the kind in which air is compressed in the crank case of the engine by the downward thrust of the piston, the compressed air being conducted to the cylinder and there utilized to support combustion and to force the fuel from the fuel chamber into the cylinder when the inlet port is uncovered by the piston.

15 In some engines of this type the fuel is conveyed from the fuel chamber or other source of supply to the cylinder by means of a pipe leading through a chamber to a nozzle, a non-return valve being disposed between the nozzle and the pipe, and the 20 amount of fuel supplied being regulated by a hand-operated valve.

25 In engines of this type the top of the piston is provided with a deflector which directs the explosive mixture upward in the cylinder.

30 The object of this invention is to provide an improved engine of this type.

According to this invention the valve placed in the passage between the crank case and the cylinder and oscillated under the action of the governor to cover and uncover a port is cam-shaped, the curve of its periphery being first steep so as to rapidly cover the port during the first part of its movement, the steep part being followed by a rather a flat curve, so that the port holes are allowed to remain unaltered by the action of the governor for a certain further range of movement, this portion being followed by a sudden rise or steep curve which completely covers the port holes when the speed reaches a certain predetermined velocity.

35 In use when the engine is at rest the port holes are fully open. When the engine is started the engine governor causes the disk valve to be moved on its axis so that when the engine reaches its normal speed the disk valve commences to cover the port holes, and

immediately the speed increases, the port holes become nearly covered by the effect of 40 the steep curve of the periphery of the valve, leaving only a comparatively small opening. The port holes are allowed to remain unaltered by the action of the governor for a certain further range of movement which is 45 effected by the flat curve following the steep curve above referred to. Finally the speed reaches a point when the disk valve completely covers the port holes due to the sudden or steep curve of the valve. 50

55 It has been found with oil engines of the types referred to that slight variations and inaccuracies which arise in the course of manufacture in the sizes of ports and passages—and which are often unavoidable—60 affect considerably the supply of air passing to the cylinder and thereby the "running" of an engine. I modify the effect of such inaccuracies by drilling one or more holes in 65 the disk valve.

70 In an engine made in accordance with this invention the nozzle projects into the passage between the crank chamber and the cylinder whereby fuel is drawn into the nozzle during the suction period of the crank chamber cycle. It is provided with an air passage for the purpose of admitting air during the compression period of the crank chamber cycle to mix with and atomize the fuel, but in my improved design this air passage is 75 now made very short and is not provided with an air chamber. I place the non-return valve in or close to the chamber in which the oil is located prior to it being drawn into the cylinder, in which position it is always covered with fuel oil, and never in contact with air nor with the products of combustion 80 which would be liable to set up corrosion. 85

90 The cylinder head of the engine is made in a shape corresponding approximately 95 with that of the deflector on the piston, and when the piston is at the point of highest compression, the whole charge is compressed into the cylinder head. The effect of this is that when the mixture of fuel and air 100 enters the cylinder and is directed upward into the cylinder head with the piston also traveling rapidly in the same direction the combustible mixture compressed into the cylinder head is richest on that side of the 105 deflector against which the incoming charge

impinges. It is at this place that the 65
sparking plug is fixed in order to obtain the
explosion with greatest certainty.

Figure 1 of the drawings is a sectional
5 elevation of an engine made in accordance
with this invention;

Fig. 2 is a detail of the valve *g*.

Fig. 3 shows the valve in another position.

10 The engine comprises any desired number
of cylinders *a* disposed vertically and each
provided with an independent crank chamber
75 *b* connected to the combustion chamber
of the corresponding cylinder by an air
passage *c* opening into the cylinder at *d*.
The lower face of each piston *e* acts in the
known way as a pump to draw air through
the valve *f* into the crank case *b* on its up
stroke and to compress it therein on its
20 down stroke. The connection between each
crank case *b* and the corresponding air pas-
sage *c* is regulated by a plate valve *g* con-
trolled by the engine governor.

25 In the passage *c* is a fuel nozzle *h* which
projects into the cylinder air port *d*. Liquid
fuel is supplied by the pipe *k* to the reser-
voir *m* and from thence by a pipe *n* through
the chamber *o* to the nozzle *h*. A non-re-
turn valve *p* is disposed in the chamber *o*
30 and a hand-operated valve *q* is disposed in
the pipe *n* to regulate the supply of fuel
to the nozzle. Between the nozzle *h* and
the valve *g* an orifice *h'* is made communi-
cating with the air space around the nozzle.
35 The reservoir *m* may be provided with a
float if desired to control the flow of liquid.
The valve *g* may be provided with holes *g'*
and may be formed with curved faces *r*
and *s* working over two or more holes such
40 as *t* to regulate the quantity of air. The
small holes *g'* of the disk valve can be
drilled to any suitable size and form a con-
venient method of increasing the air supply
to any degree which may be found neces-
45 sary when testing the engine in order to
correct the variations and inaccuracies
which arise in the course of manufac-
turing. It has the advantage that the addi-
tional area of the opening thus secured re-
50 mains constant for a considerable move-
ment of the disk valve across the opening.
Fig. 3 shows the disk valve moved to a po-
sition leaving only a comparatively small
opening in the port hole. *u* is a lubricator
55 from which oil is conveyed to the crank
case through the air valve *f*. The inside of
the cylinder head is shaped as at *v* corre-
sponding approximately with the shape of
the deflector *x*. The sparking plug *w* is
60 placed at a point where the explosive mix-
ture is richest.

When the piston is up, the holes at *h* and
h' in the fuel nozzle are acted upon by the
vacuum in the crank case whereby the fuel

is sucked into the nozzle. When the pis- 65
ton is down, the pressure in the crank case
acts through the hole *h'* upon the fuel in the
nozzle and drives it out through the hole *h*
which is subject to the atmospheric pres-
sure existing in the cylinder. 70

What I claim and desire to secure by Let-
ters Patent is:—

1. An internal combustion engine com-
prising a cylinder, a piston working in said
cylinder, a crank chamber, a combustion 75
chamber disposed at one end of said cylin-
der, means for admitting air to said crank
chamber, a passage from said crank cham-
ber to said combustion chamber, a source of
fuel supply, a nozzle adapted to discharge 80
into said cylinder, a fuel supply conduit
leading to said nozzle, a non-return valve in
said conduit, an air inlet from said passage
to said nozzle, said air inlet being disposed
between the end of the nozzle and the non- 85
return valve, ports in said passage between
the said nozzle and said crank chamber,
means for rapidly closing the said ports
to a predetermined area on the speed of the
engine attaining a predetermined velocity, 90
for leaving the ports unaltered during a pre-
determined range of variation of velocity,
and for closing the port when the speed of
the engine attains a certain higher prede- 95
termined velocity, said ports being opened
conversely as the speed of the engine falls.

2. An internal combustion engine com-
prising a cylinder, a piston working in said
cylinder, a crank chamber, a combustion 100
chamber disposed at one end of said cylin-
der, means for admitting air to said crank
chamber, a passage from said crank cham-
ber to said combustion chamber, a source of
fuel supply, a nozzle adapted to discharge 105
into said cylinder, a fuel supply conduit
leading to said nozzle, a non-return valve in
said conduit, an air inlet from said passage
to said nozzle, said air inlet being disposed
between the end of the nozzle and the non- 110
return valve, ports in said passage between
the said nozzle and said crank chamber, a
disk valve disposed in said passage to cover
and uncover said ports, means for imparting
angular movement to said disk valve, the 115
curve of the periphery of said disk valve
being first steep, followed by a flat curve,
followed by a sudden rise.

3. An internal combustion engine com-
prising a cylinder, a piston working in said
cylinder, a crank chamber, a combustion 120
chamber disposed at one end of said cylin-
der, means for admitting air to said crank
chamber, a passage from said crank cham-
ber to said combustion chamber, a source of
fuel supply, a nozzle adapted to discharge 125
into said cylinder, a fuel supply conduit
leading to said nozzle, a non-return valve in
said conduit, an air inlet from said passage

- to said nozzle, said air inlet being disposed between the end of the nozzle and the non-return valve, ports in said passage between the said nozzle and said crank chamber, a 5 disk valve disposed in said passage to cover and uncover said ports, means for imparting angular movement to said disk valve, the curve of the periphery of said disk valve being first steep, followed by a flat curve, 10 followed by a sudden rise.
4. An internal combustion engine comprising a cylinder, a piston working in said cylinder, a crank chamber, a combustion chamber disposed at one end of said cylinder, means for admitting air to said crank chamber, a passage from said crank chamber to said combustion chamber, a source of fuel supply, a nozzle adapted to discharge into said cylinder, a fuel supply conduit 15 leading to said nozzle, a non-return valve in said conduit, an air inlet from said passage to said nozzle, said air inlet being disposed between the end of the nozzle and the non-return valve, ports in said passage be- 20 tween the said nozzle and said crank chamber, a disk valve disposed in said passage to cover and uncover said ports, means for imparting angular movement to said disk valve, the curve of the periphery of said disk valve 25 being first steep, followed by a flat curve, followed by a sudden rise, means for correcting the variations and inaccuracies 30 which arise in the manufacture in the sizes of ports and passages, said means comprising at least one hole in said cam shaped disk valve.
5. An internal combustion engine comprising a cylinder, a piston working in said cylinder, a crank chamber, a combustion chamber disposed at one end of said cylinder, means for admitting air to said crank chamber, a passage from said crank chamber to said combustion chamber, a source of fuel supply, a nozzle adapted to discharge 40 into said cylinder, a fuel supply conduit leading to said nozzle, a non-return valve in 45
- said conduit, an air inlet from said passage to said nozzle, said air inlet being disposed between the end of the nozzle and the non-return valve, ports in said passage between the said nozzle and said crank chamber, a disk valve disposed in said passage to cover and uncover said ports, means for imparting angular movement to said disk valve, the curve of the periphery of said disk valve 55 being first steep, followed by a flat curve, followed by a sudden rise, said piston being provided with a deflector and said combustion chamber being formed to correspond approximately with the shape of the deflec- 60 tor.
6. An internal combustion engine comprising a cylinder, a piston working in said cylinder, a crank chamber, a combustion chamber disposed at one end of said cylinder, means for admitting air to said crank chamber, a passage from said crank chamber to said combustion chamber, a source of fuel supply, a nozzle adapted to discharge into said cylinder, a fuel supply conduit 65 leading to said nozzle, a non-return valve in said conduit, an air inlet from said passage to said nozzle, said air inlet being disposed between the end of the nozzle and the non-return valve, ports in said passage between the said nozzle and said crank chamber, a disk valve disposed in said passage to cover and uncover said ports, means for imparting angular movement to said disk valve, the curve of the periphery of said disk valve 70 being first steep, followed by a flat curve, followed by a sudden rise, and means for supplying oil from a level above said non-return valve.
- In witness whereof, I have hereunto signed 80 my name in the presence of two subscribing witnesses.
